UNITED STATES PATENT OFFICE.

HARRY O. PITTS, OF CARTHAGE, INDIANA.

IRONING-BOARD.

1,155,612.

Specification of Letters Patent.

Patented Oct. 5, 1915.

Application filed March 22, 1915. Serial No. 16,223.

To all whom it may concern:

Be it known that I, HARRY O. PITTS, a citizen of the United States, residing at Carthage, in the county of Rush, State of Indiana, have invented certain new and useful Improvements in Ironing-Boards; and I do hereby declare the following to be a full, clear, and exact description of the invention, such as will enable others skilled in the art to which it appertains to make and use the same.

This invention relates to certain novel and useful improvements in ironing boards or tables.

15 In carrying out my invention it is my purpose to provide an ironing board having supporting devices which are so constructed and arranged that when extended these devices are adapted to support the board in position for ironing, while when collapsed the supporting devices will lie over against the underside of the body of the board so that the entire structure will occupy but relatively little space in storage or in shipment.

Still a further object of my invention is the provision of an ironing board of this type wherein when it is desired to open the board or extend the same in position for operation, it is only necessary to grasp one end of the board and pull or lift the same so that the supporting device will drop into supporting position relative to the board, while when it is desired to collapse or fold 35 the board, as for storage, it is only necessary to lift or tilt one end of the board so that lateral pressure against certain of the leg sections of the supporting device will cause such device to collapse or fold against the bottom of the board.

Still a further object of my invention is the provision of means whereby the supporting device of the board may be locked in both collapsed and extended positions. I 45 also propose to provide a board of this character which will embody in its construction the desired features of simplicity, efficiency and convenience, and which composed as it is of but relatively few parts, may be manufactured and marketed at a comparatively low cost.

With the above recited objects and others of a similar nature in view, my invention consists in the construction, combination and arrangement of parts set forth in and

falling within the scope of the appended claims.

In the accompanying drawings: Figure 1 is a view in side elevation of an ironing board embodying my invention. Fig. 2 is a bottom plan view thereof and showing the supporting devices in their folded or collapsed position against the bottom of the board. Fig. 3 is an end view. Fig. 4 is a vertical sectional view taken on the line 4-4 of Fig. 1.

Referring now to the accompanying drawings in detail, the letter A indicates the ironing board or table proper, which may be of any ordinary and well known form. To the bottom thereof adjacent one end is secured the spaced bearing blocks 1-1 supporting the cross shaft 2. Pivotaly supported on the ends of this shaft are the parallel legs 3-3 which form the vertical supporting legs for the device. Attached to the outer side of each leg 3 is an inclined brace leg 4, these legs 3 and 4 being connected and strengthened by the cross bar 5. The numeral 6 designates a relatively long central supporting leg which is pivoted adjacent its upper end to the cross shaft 2 between the blocks 1, and is beveled at such end portion as at 7 so that the leg may be readily folded and extended. When in its extended position, this leg 6 forms a diagonal or inclined support for the board with its lower beveled end 8 resting upon the floor.

At 9-9 I have shown a pair of parallel arms which are spaced apart and hinged as at 10 to the bottom or underside of the board. Adjacent their lower ends these arms are bored transversely as at 11 for the passage of the bight portion of the relatively long U-shaped yoke member 12, the terminals of the arms 13 of which are secured to the legs 3-3. This yoke member is formed from a metal bar bent into U-shape form, and the bight portion thereof which connects the two arms 9-9 also passes through the elongated slot 14 formed in the diagonal supporting leg 6, this leg passing between the arms 9 as clearly shown in the drawing. The upper end portion of the slot is formed with a lateral notch 15 so that when the board is in its extended position the bight of the yoke member will drop into this notch and thus hold the parts against accidental collapse. In this connection I

wish to call attention to the fact as the yoke member is connected to the vertical legs 3-3 and also to the arms 9-9, while slidingly connecting said arms with the diagonal supporting leg, it is only necessary in collapsing the board to grasp the reduced end portion *a* of the board and lift slightly and then push toward the opposite end of the board so that a lateral pressure will be brought against the ends of the legs 3 to force the latter inward toward the board, and with this movement motion is transmitted through the yoke member to the arms 9 so that the latter will be forced against the bottom of the board A, at the same time pulling with them the diagonal brace rod. To open the board, it is also only necessary to grasp this end *a* and lift it when the entire supporting device will drop into position of its own weight. Furthermore, it is to be noted that by coupling the arms and the brace bar with the vertical legs through the medium of the yoke member, such yoke member will when the board is assembled ready for use, prevent the diagonal brace leg from swinging or pulling loose. For instance, should the board be accidentally moved, this yoke interlocking as it does with the diagonal supporting leg will prevent the collapse of the parts.

In order to fasten the supporting devices in collapsed position against the bottom of the board when it is desired to store or ship the board, I provide a turn latch L fastened to the under edge of the diagonal supporting leg 6, and when the supporting devices are collapsed against the board, this latch is adapted to be turned to engage or interlock with the cross bar 5, thus holding the parts against movement.

What I claim is:

1. The combination with a body board, of a pivot shaft suspended from the underside of the board adjacent one end thereof, a

pair of parallel legs carried by the pivot shaft, inclined brace legs carried by the parallel legs, a cross bar connecting the parallel legs and the brace legs, a diagonal supporting leg pivoted to the shaft at one end intermediate the parallel legs, said diagonal supporting leg having an elongated slot therein terminating in a notch, a pair of spaced arms hinged to the bottom of the body board and between which arms the diagonal supporting leg extends, and a relatively long U-shaped yoke member having its bight portion passing through the free end portions of the arms and through the slot in the diagonal supporting leg, the terminals of the yoke being fastened to the parallel legs.

2. The combination with a board, of a pair of parallel legs pivotally connected with the bottom of the board adjacent one end thereof, a diagonal supporting leg pivotally connected with the bottom of the board at one end at a point between the parallel legs, said diagonal leg having a relatively long slot therein terminating at its upper end in a lateral notch, a pair of parallel spaced arms hinged to the bottom of the board and between which arms the diagonal brace extends, and a relatively long U-shaped yoke member having its bight portion extending through the free end portions of the arms and through the slot portion of the diagonal supporting leg, the terminals of said U-shaped member being connected with the parallel supporting legs, the bight of said yoke member resting in the notch at the end of the slot when the device is in its extended operative position.

In testimony whereof, I affix my signature, in the presence of two witnesses.

HARRY O. PITTS.
